Primary Examiner—Jeffrey Asch*Attorney, Agent, or Firm*—Chrisman, Bynum & Johnson[57] **CLAIM**

The ornamental design for a miniature portable corded phone base, as shown and described.

DESCRIPTION

FIG. 1 is a left side front perspective view of a miniature portable corded phone base showing my new design; show in phantom is a telephone headset resting therein.

FIG. 2 is a left side elevation view;

FIG. 3 is a top plan view;

FIG. 4 is a right side elevation view;

FIG. 5 is a bottom elevation view;

FIG. 6 is a rear elevation view; and,

FIG. 7 is a front elevation view.

The broken line showing of a telephone headset in FIG. 1 is for illustrative purposes only and forms no part of the claimed design.
